HIS ATTORNEY

UNITED STATES PATENT OFFICE.

EDWIN E. BARNEY, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 852,313.

Specification of Letters Patent.

Patented April 30, 1907.

Application filed November 29, 1904. Serial No. 234,764.

To all whom it may concern:

Be it known that I, EDWIN E. BARNEY, a citizen of the United States, and a resident of Syracuse, in the county of Onondaga and the State of New York, have invented certain new and useful Improvements in Type-Writing Machines, of which the following is a specification.

This invention relates to typewriting machines and more particularly to the type bar actuating mechanism of such machines.

The main object of the invention is to provide an improved construction of joint or connection between certain of the members of the type bar actuating mechanism.

Other objects will subsequently appear.

To the above ends my invention resides in the features of construction, arrangements of parts and combinations of devices to be hereinafter more fully described and particularly pointed out in the appended claims.

In the accompanying drawings, Figure 1 is a skeleton view in side elevation of a type bar and its actuating mechanism. Fig. 2 is an enlarged fragmentary side view of the upper portion of a sub-lever. Fig. 3 is a sectional view taken on the line $x-x$ of Fig. 2. Fig. 4 is an enlarged detail view showing the rear end of a connecting link.

In the drawings, 1 indicates a fulcrum plate attached to the frame 2 of the machine, 3 one of a series of key levers slotted at 4 so as to embrace a fixed bar 5 and each provided with a restoring spring 6 and key cap 7. A sub-lever 8 is pivoted at 9 to each key lever and the lower end of said sub-lever is slotted or recessed at 10 in order to co-act with a fixed fulcrum rod 11 which passes from side to side of the machine, beneath the series of key levers. The upper end of each sub-lever 8 is connected by a link 12 with a type bar 13 in a manner presently to be more fully described. Each type bar is provided with a type block 14 carrying one or more types.

The free ends of the series of type bars are normally supported by a type rest 15 and the types are adapted to strike against the face of a platen 15^a. At its pivotal end, each type bar is seated in a slot 16 formed in a segmented type bar support 17 which slot is one of a radially arranged series, and the heel of said type bar is perforated to permit of the passage of a fulcrum wire 18 which is secured in the top of the type bar support 17.

I do not desire to be limited to the particu-

lar construction of pivotal support for the type bar as shown and described; other styles of support may be employed equally as well. It will be apparent that the construction and arrangement of parts as hereinbefore set forth is similar in most respects and may be said generally to be that of the Monarch typewriting machine, but my invention may be adapted and applied to other forms of writing machines.

Referring now more particularly to the novel features wherein my invention resides and considering especially Figs. 2 and 3, each connecting link 12 has secured at its rear end a pin 19 which projects from the side of said link at right angles to the body portion thereof and terminates in a circular head 20, the end or lower portion of said head being flattened or cut away at 21 (Fig. 4). At its top, each sub-lever 8 is formed with a vertical elongated slot 22 larger in diameter at the bottom than at the top and which, for convenience, will be called a key-hole slot. Secured to the sub-lever below the key-hole slot in any suitable manner as by a rectangular rivet 23 is a flat locking spring 24, the free end of which is bent inward at 25 so that it normally stands within the key-hole slot and terminates at a distance below the top of said slot slightly greater than the diameter of the pin 19.

By this arrangement under any stress tending to withdraw the pin 19 from the key-hole slot the under side of the head 20 of said pin is caused to engage with the face of the sub-lever 8 above the top of the key-hole slot and thus the link is prevented from being accidentally separated from the sub-lever. The locking spring 24 is formed near its free end with side lugs 26 by which it may be conveniently pulled away from the sub-lever until the free end of the locking spring is withdrawn from the slot, moving longitudinally of the pin 19. The end of the spring is pulled away sufficiently to admit of the pin 19 being withdrawn from the wider end of the key-hole slot, so as to disconnect the link 12 from the sub-lever 8. The joint 27 between each type bar and its connecting link may be of any desired construction.

In practice, the type bars and their associate links are assembled before being secured in place on the type bar support 17, and the key levers and their associate sub-levers are separately assembled and mounted.

in the machine. The pin 19 on each connecting link or member 12 will now be snapped into place in the key-hole slot in the sub-lever, and the type action is thereby completely assembled. Taking the steps of what may be called the "snapping in" process in order: the pin 19 is first passed through the wider portion of the key-hole slot 22 of its associate sub-lever or actuating member, the head 20 of said pin pushing the spring 24 away from the face of the sub-lever; next the pin 19 is lifted to the upper narrow portion of said slot and over the free end of the spring and thus locked in place by the latter, which 15 snaps back into normal position. The cut-away 21 in the head of the pin 19 enables the top of the locking spring 24 to be arranged close enough to the top of the key-hole slot to permit a snug fit of the pin 19 to be obtained, thereby preventing looseness and rattle in the connection.

Various changes may be made without departing from the spirit and scope of my invention.

25 What I claim as new and desire to secure by Letters Patent, is:—

1. In a typewriting machine, the combination of an actuating member; a connecting member, one of said parts being formed with 30 a key-hole slot and the other with a headed pin adapted to enter the wider part of said slot; a flat spring secured to the face of one of said members and adapted to maintain the headed pin in the narrow end of the key-hole slot; and a type bar connected with said connecting member.

2. In a typewriting machine, the combination of an actuating lever; a connecting link, one of said parts being formed with a key-hole slot and the other with a headed pin adapted to enter the wider part of said slot; a flat spring riveted to the face of one of said parts and adapted to maintain the headed pin in the narrow end of the key-hole slot; and a type bar connected with said connecting link.

3. In a typewriting machine, the combination of an actuating member; a connecting member, one of said members being formed 50 with a key-hole slot and the other with a headed pin adapted to enter the wider part of said slot; a spring on one of said members, said spring being adapted to maintain the headed pin in the narrow end of the key-hole slot and to release said pin by being pulled away from the face of the part on which said spring is secured; and a type bar connected with one of said members.

4. In a typewriting machine, the combination of an actuating member; a connecting link, one of said parts being formed with a key-hole slot and the other with a headed pin adapted to enter the wider part of said slot; a flat spring secured to the face of one of said 65 parts and adapted to maintain the headed

pin in the narrow end of the key-hole slot and to release said pin by being pulled away from the face of the part to which it is secured; and a type bar connected with said connecting link.

5. In a typewriting machine, the combination of an actuating member; a connecting member, one of said members being formed with a key-hole slot and the other with a headed pin adapted to enter the wider part of 75 said slot; a spring on one of said members, said spring being adapted to maintain the headed pin in the narrow end of said key-hole slot and to release said pin by being moved longitudinally of the latter; and a 80 type bar connected with said connecting member.

6. In a typewriting machine, the combination of an actuating member; a connecting member, one of said members being formed 85 with a key-hole slot and the other with a headed pin adapted to enter the wider part of said slot; a spring secured to one of said members, the free end of said spring normally standing within the key-hole slot and being adapted to maintain the headed pin in the narrow end of said slot and to release said pin by being withdrawn from said slot; and a 90 type bar connected with said connecting member.

7. In a typewriting machine, the combination of a type bar; a lever formed with a key-hole slot; a connecting link carrying a headed pin adapted to enter the wider part of said key-hole slot; and a spring secured to the 100 face of said lever, the end of said spring being adapted to maintain the headed pin in the narrow end of the key-hole slot and to release said pin by being pulled away from the face of said lever.

8. In a typewriting machine, the combination of an actuating member; a connecting member, one of said parts being formed with a key-hole slot and the other with a headed pin adapted to enter the wider part of said 110 slot; a flat spring secured to the face of one of said members and adapted to maintain the headed pin in the narrow end of the key-hole slot and to permit rotary movement of said pin therein; and a type bar connected 115 with said connecting member.

9. In a typewriting machine, the combination of an actuating member; a connecting member, one of said members being formed with a key-hole slot and the other with a headed pin adapted to enter the wider part of 120 said slot; a spring on one of said members, said spring being adapted to maintain the headed pin in the narrow end of the key-hole slot and to permit rotary movement of said pin in said narrow end, said spring being further adapted to release said pin by being pulled away from the face of the part on which said spring is secured; and a type bar connected with one of said members.

10. In a typewriting machine, the combination of an actuating member; a connecting link, one of said parts being formed with a key-hole slot and the other with a headed pin adapted to enter the wider part of said slot; a flat spring secured to the face of one of said parts and adapted to maintain the headed pin in the narrow end of the key-hole slot and to permit rotary movement of said pin while so maintained, said spring being further adapted to release said pin by being pulled away from the face of the part to which it is secured; and a type bar connected with said connecting link.
11. In a typewriting machine, the combination of an actuating member; a connecting member, one of said members being formed with a key-hole slot and the other with a headed pin adapted to enter the wider part of said slot; a spring secured to one of said members, the free end of said spring normally standing within the key-hole slot and being adapted to maintain the headed pin in the narrow end of said slot and to release said pin by being moved longitudinally of the latter until withdrawn from said slot; and a type bar connected with said connecting member.
12. In a typewriting machine, the combination of a type bar, a lever formed with a key-hole slot; a connecting link carrying a headed pin adapted to enter the wider part of said key-hole slot; and a spring secured to the face of said lever, the end of said spring being adapted to maintain the headed pin in the narrow end of the key-hole slot and to permit rotary movement of said pin while so maintained, said spring being further adapted to release said pin by being pulled away from the face of said lever.
13. The combination with two members one of said members having a slot, a pin extending from the other member through the slot and having a head provided with a flat side next to the open end of the slot, of a spring on the slotted member provided with a tongue entering the slot past the flattened side of the head.

Signed at Syracuse, in the county of Onondaga, and State of New York, this 26th day of November A. D. 1904.

EDWIN E. BARNEY.
